UNITED STATES PATENT OFFICE.

SAMUEL MCCOMB AND JAMES B. MCCOMB, OF NEW YORK, N. Y.

WASHING COMPOUND.

1,264,104.

Specification of Letters Patent. Patented Apr. 25, 1918.

No Drawing.

Application filed September 13, 1916. Serial No. 118,852.

To all whom it may concern:

Be it known that we, SAMUEL MCCOMB, a citizen of the United States, and JAMES B. MCCOMB, a subject of the King of England, both residing at New York, in the county of Bronx and State of New York, have invented a new and useful Washing Compound, of which the following is a full, clear, and exact specification.

10 This invention relates to detergents or washing compounds adapted for cleaning or renovating carpets and rugs, and also useful for washing clothes and other fabrics.

It is the object of this invention to provide an improved compound of this kind which may be used in connection with any good white soap for cleaning and restoring the luster to carpets and rugs, and for cleansing and whitening clothes as well as 15 removing dirt, stains and disagreeable odors without injury to the article treated and without any great amount of rubbing. A special object is to provide a compound of this kind which may be used on carpets and 20 rugs made with inferior dyes without danger of the colors running. It has been found that the use of hot water in connection with our formula covered in U. S. Patent No. 1,172,297, issued February 22, 1916, has a 25 tendency to make the colors run on carpets and rugs made with the inferior dyes now available in this country owing to the European war, whereas cold water used with the new formula given herein does not have this 30 detrimental effect.

Another object is to provide a washing compound which may be used with soap instead of having soap incorporated therein and give the same beneficial results. The 40 omission of the soap from the compound makes it possible to supply the public with the cleaning compound at a greatly reduced cost owing to the reduction in transportation charges due to the decrease in bulk.

Our present composition consists of the following ingredients, combined in the proportions stated:

Pure powdered borax	6 lbs.
Soda ash	3½ lbs.
Ultramarine blue, powdered	½ lb.
Glycerin	8 oz.
Pure oil of cedar leaves	3 oz.

In preparing the compound, the first three 55 ingredients, which are in powdered form, are placed in a rotary mixer and the latter

permitted to revolve very rapidly for about three minutes. The glycerin and oil of cedar leaves are then dropped in and the mixer allowed to rotate for another minute 60 or so, or the whole process of mixing may be shortened into the space of three minutes. The rapid rotation of the mixer causes the ingredients to become uniformly mixed and leaves the mass in powdered form. 65

For use, one ounce of the above compound is dissolved in one gallon of cold water, and the resulting solution used with a cake of white soap for cleaning carpets and rugs in the following manner: The soap is dipped 70 into the solution and rubbed over the article to be cleaned, and while still damp additional quantities of the solution are applied with a cloth by which both the solution and soap are rubbed well into the fabric. After 75 being allowed to dry, the article is in just as good condition as when the formula given in our Patent 1,172,297 is used, and the cold solution applied with a cloth does not saturate the article sufficiently to cause the colors 80 to run even when inferior dyes have been used in making the article, as might result from the use of the hot solution applied more lavishly with a brush according to said patent. 85

When the compound is to be used for washing clothes, one ounce thereof together with about a cake of soap is added to a wash boiler full of clothes and boiled for 15 or 20 minutes. The clothes are then 90 rinsed in the usual way and hung out to dry. There is absolutely no necessity for rubbing the clothes on a wash board, and the wear and tear is therefore greatly reduced. The compound when used in this way not only 95 saves time and labor but gives superior results by removing stains, disagreeable odors and all dirt, leaving the clothes as white as snow.

We have discovered, that our patented 100 compound, by the elimination of soap can be dissolved in cold water, and used cold for cleaning, without forming a jelly, and give better results, than if used hot with soap in it. By the use of the above formula minus 105 the soap, and by using the above formula, as above described, no likelihood of jellifying is present, as would occur, if our patented formula was mixed with hot water and then allowed to cool. Therefore, it is 110 important that the distinction between our patented formula, which contains soap and

our present formula which contains no soap, as well as the use of hot water in our patented formula, and the use of cold water in the above formula, be clearly understood. 5 By the use of cold water in mixing the above formula, we are thus overcoming the likelihood of spreading inferior present day dyes, used in coloring effects on rugs and carpets, etc., and the use of cold water, 10 therefore, becomes of great beneficial convenience.

We have, further, discovered that in applying the above formula or cleaning compound by means of a cloth moistened in the 15 above formula, that it is quite impossible to saturate a carpet or rug carelessly or unintentionally, as could easily happen by the careless use of a brush dipped in the prepared solution of our above formula.

20 All of which is made possible by eliminat-

ing the soap in our patented formula from the above formula and using soap separate from the other ingredients, and as is herein before described.

Having thus described our invention, what 25 we claim as new and desire to secure by Letters Patent of the United States is:—

1. A compound in powdered form, consisting of borax, soda ash, ultramarine blue, glycerin and oil of cedar leaves. 30

2. A compound in powdered form, consisting of the following ingredients in substantially the proportions named, viz: 6 lbs. of borax, $3\frac{1}{2}$ lbs. of soda ash, $\frac{1}{2}$ lb. of ultramarine blue, 8 oz. of glycerin, and 3 oz. of 35 oil of cedar leaves.

In testimony whereof we have signed our names to this specification.

SAMUEL McCOMB.
JAMES B. McCOMB.
